WHEELED WHIRLING TOY

Silas M. Ford, St. Paul, Minn.

Application April 4, 1956, Serial No. 40,899

Term of patent 14 years

(Cl. D34—15)

FIG. 1

FIG. 2

FIG. 3

FIG. 4

Fig. 1 is a perspective view of a wheeled whirling toy, showing my new design;

Fig. 2 is a side elevational view thereof, to an enlarged scale;

Fig. 3 is a rear elevational view thereof, to an enlarged scale; and

Fig. 4 is a top plan view thereof to an enlarged scale.

Portions of the handle have been broken away in the drawing figures for convenience of illustration.

I claim:

The ornamental design for a wheeled whirling toy, as shown and described.
